Attorney, Agent, or Firm—Jenkins & Gilchrist, P.C.

[57] CLAIM

The ornamental design for the backplate for a lighting fixture, as shown and described.

DESCRIPTION

FIG. 1 is a top front perspective view of a backplate for a lighting fixture showing my design;

FIG. 2 is a front elevational view;

FIG. 3 is a right side elevational view, the left side being a mirror image of the right side;

FIG. 4 is a rear elevational view;

FIG. 5 is a top plan view; and,

FIG. 6 is a bottom plan view.

The broken lines show the environment in which the article is used and are not considered part of the design claimed.
